UNITED STATES PATENT OFFICE.

FREDERICK B. SPROSS, OF CHURCHVILLE, NEW YORK.

PULVERIZER.

1,149,414.

Specification of Letters Patent. Patented Aug. 10, 1915.

Application filed February 17, 1912. Serial No. 678,395.

To all whom it may concern:

Be it known that I, FREDERICK B. SPROSS, a citizen of the United States, residing at Churchville, in the county of Monroe and 5 State of New York, have invented certain new and useful Improvements in Pulverizers, of which the following is a specification.

The object of my invention is to provide 10 an improved pulverizer to work on farm land to prepare it for planting.

The machine which constitutes the subject matter of my invention is to be drawn over the ground, breaking up the top surface 15 and pulverizing and leveling it off as it goes.

Another object of my invention is to provide means for increasing and diminishing the pulverizing action of the machine.

Another object of my invention is to support 20 the elements of the machine so that they may be lowered into contact with the ground or raised from it to facilitate transportation of the machine when it is not intended to have its pulverizing action.

25 These and other objects of my invention will be fully illustrated in the drawings, described in the specification and pointed out in the claims at the end thereof.

In the accompanying drawings, Figure 1 30 is a top plan view of the machine. Fig. 2 is a rear elevation of the machine. Fig. 3 is a longitudinal horizontal section of one of the pulverizing rollers. Fig. 4 is a front elevation of the machine. Fig. 5 is a section on 35 the line 5^x-5^x of Fig. 1. Fig. 6 is a detail perspective view of the pulverizing roller and supports or braces for the blade therefor. Fig. 7 is a detail perspective view of the complete cutting blade. Fig. 8 is a plan 40 view of the roller, showing a double set of the cutting blades thereon, the forward set being staggered with reference to the rear set. Figs. 9 and 10 are detail views of special forms of blades that may be used in 45 connection with the rollers. Fig. 11 is a detail perspective view of the channels 37 and 38, showing the device for giving angular adjustment to the rollers. Fig. 12 is a detail view of the locking device for holding the 50 frame at any desired elevation.

In the accompanying drawings like reference numerals refer to like parts.

In the drawings, reference numeral 1 indicates the frame of my pulverizer, on 55 which are mounted the supporting shafts 2 and 3, at the crank ends of which as shown

in Fig. 2 the supporting wheels 4 and 5 of the machine are mounted to rotate. The crank shafts 2 and 3 are provided for the purpose of carrying the machine at different 60 elevations on the wheels. When raised the frame will carry the pulverizing rollers clear of the ground, and when lowered the pulverizing rollers will be dragged in contact with the ground. The shafts 2 and 3 65 can be keyed to or clamped to the frame in either of the several positions, so that the frame of the machine can be kept uniformly at any desired height. To raise and lower the machine I provide the sprocket wheels 70 6 and 7 on the shafts 3 and 2. I also provide the sprocket chains 8 and 9 which engage with these sprocket wheels and which are in turn driven by the sprocket gears 10 and 11, which gears are mounted upon the 75 crank shafts 13 and 14 having handles on the inner ends thereof. By the rotation of these shafts the sprocket chains 8 and 9 are turned and the shafts 3 and 2 are rotated, causing them to be raised or lowered with 80 reference to the supporting wheels of the machine.

The machine comprises a rectangular frame having the sill 15 at the front and the sill 16 at the back, and the intermediate sills 85 21 and 22 parallel thereto, connected by the cross bars 17, 18, 19 and 20, all connected firmly together in any suitable manner. Suspended from the sill 15 by the brace rods 23 to 36 inclusive is the front channel iron 90 37, which channel iron is rigid with reference to the frame of the machine. Mounted to slide in this channel is the movable channel 38, which channel is longitudinally adjustable back and forth for a purpose that 95 will presently be described. The top and bottom flanges of the channel 38 are perforated with five holes which are spaced approximately two inches between centers, and a single hole is put through the top and 100 bottom flanges of the channel 37. A pin 39 is used to pin the inner channel and the outer channel together at the left hand end, as shown in Fig. 4. The other end of the channel 38 is held in place by guide flanges 105 40 and 41 riveted to the outer channel 37, or in any other suitable manner. This arrangement permits the easy longitudinal adjustment of the inner channel on the outer channel, for a purpose which I will now 110 describe.

Mounted below the sill 16 is the support-

ing channel 42, from which it is suspended by the braces 60 to 71 inclusive. Other braces such as are shown at 72 and 73 are shown for the purpose of bracing the channels 37 and 42 laterally to the intermediate sills 21 and 22 of the frame. The shaft 75 by which the machine is drawn is attached to the frame of the machine and braced by the side braces 76 and 77.

10 Mounted in the channels 42 and 38 are the trunnion bearings 43, which trunnion bearings are swiveled in the channel so as to swing around a vertical axis. These bearings support the shaft 44 which carries the 15 rollers 45. These shafts are preferably square shafts having rounded ends with which they engage the bearings. As shown in Fig. 1, six of these rollers are preferably provided in my improved machine. Each 20 one is supported by the shaft, which shaft engages with a trunnion bearing carried at the front of the machine and a similar trunnion bearing carried at the rear of the machine. As is illustrated in Fig. 1, these 25 rollers 45 or their supporting shafts are placed at an acute angle to the sills of the framework of the machine, and by moving the channel 38 this acute angle may be varied within considerable limits, leaving 30 them in the position shown in Fig. 1, or so as to bring them almost parallel to the line of travel of the machine, as may be desired, for purposes that will presently appear.

The roller 45 is a cone shaped shell or 35 drum formed preferably of sheet metal, either wrought iron or steel, the ends of which are closed front and back for the purpose of receiving the supporting shaft therein. This drum is perforated with rectangular openings 46, 46 at suitable intervals, these openings being spaced apart in several rings arranged around the drum as may be desired. The braces 47 are provided with hooks 48 on the lower edge thereof, 45 which hooks pass through the recesses 46 and extend into the interior of the drum and engage therewith when the brace 47 is shifted rearwardly. To this brace are riveted the cutting blades 48 and 49 as 50 shown in perspective in Fig. 7, which blades come together at the top to form a blunt cutting edge, and are spread at the bottom to obtain a firm lateral support along the roller by which they are held firmly in a 55 radial position to the drum. When the blades are all in position they may be locked in engagement with the drum by a washer 50 which is held in position by a rivet 51, or in any other suitable manner.

60 In Fig. 8 I have shown a roller with two sets of short blades instead of one set of long blades thereon. The front blades are staggered with reference to the rear blades, each of the front blades having an offset portion 65 at the rear end thereof which engages with

the front end of the rear blade adjacent thereto, so that the front blades hold the rear blades in position, and the single washer 50 which may be used for locking the front blades in position will also secure the rear blades as well. The offset portion 52 of the front blades may be cut away at the top so that it will engage with the rear blades only at the bottom. If desired, blades may be used such as are shown in Fig. 10, 70 which are formed of a single piece of metal and are bent progressively toward one side for the purpose of better engaging with and cutting the ground and moving it laterally to smooth it off as the machine passes 80 over the ground.

The rear bearings of the rollers must to some extent receive an end thrust as the machine travels forward, and both the front and the rear bearings permit the supporting 85 shaft for the rollers to rotate therein, it being understood that the rollers are left free to rotate and will in fact rotate to some extent as the machine is moved forward.

When the lateral adjustment of the channel 38 is made, it will be understood that the shafts 44 will travel in or out of the trunnion bearing 43, increasing or diminishing its bearing contact therewith. The natural tendency of the rollers to drift backward 95 will at all times keep them firmly seated in the rear bearing. The front bearings must be made sufficiently long so as to accommodate this travel in and out and still provide ample bearing surface when the channel 38 100 is moved sidewise to give the rollers the greatest angular pitch to the surface over which it may be traveling.

In the regular operation of my machine the angular adjustment of the rollers is 105 made to suit the requirements of the ground upon which it is intended to operate, a great degree of pulverizing being secured by increasing the angle which the rollers make with the line of travel of the machine, and the pulverizing being diminished by making the rollers more nearly parallel with the line of travel of the machine. After this adjustment has been made to suit the requirements of the ground on which the machine is to 115 operate, the frame is lowered to its lowest position and locked in place with the rollers in contact with the ground. As the machine travels forward, the frictional contact between the knives of the rollers and the 120 ground will cause the rollers to slowly rotate as the machine moves forward, causing it to shear the clods of earth and to distribute all of the ground uniformly, reducing it to a fine level surface. On each of the 125 shafts 2 and 3 I fasten a gear wheel 80 and 81. On the cross bars 18 and 19 adjacent thereto I mount dogs 82 and 83 which can engage with the teeth of said gears and hold the shafts 2 and 3 in any angular position. 130

This enables me to place the frame in any one of a number of elevations, as may be desired.

Having thus described my invention, what I claim as new and patentable is as follows:

1. In a pulverizer, the combination of a frame, supporting wheels therefor, rollers rotatably mounted in said frame, said rollers being mounted diagonal to said supporting wheels, and means for adjustably changing the position of said rollers at one end, said rollers having parallel axes.
2. In a pulverizer, the combination of a frame, supporting wheels thereon, stationary supporting channels mounted on said frame at the front and back thereof, a channel mounted to slide in the stationary channel at the front of the frame, trunnion bearings mounted in said sliding channel at the front of the frame and in said stationary channel at the back of the frame, said trunnion bearings being mounted to rotate around their vertical axes, rollers extending between the channels at the front and back of said frame and supported by the trunnion bearings therein.
3. In a pulverizer, the combination of a frame, supporting wheels thereon, stationary supporting channels mounted on said frame at the front and back thereof, a channel mounted to slide in the stationary channel at the front of the frame, trunnion bearings mounted in said sliding channel at the front of the frame and in said stationary

channel at the back of the frame, said trunnion bearings being mounted to rotate around their vertical axes, rollers extending between the channels at the front and back of said frame and supported by the trunnion bearings therein, said rollers being parallel to each other and placed diagonal to said frame.

4. In a pulverizer, the combination of a frame, supporting wheels thereon, stationary supporting channels mounted on said frame at the front and back thereof, a channel mounted to slide in the stationary channel at the front of the frame, trunnion bearings mounted in said sliding channel at the front of the frame and in said stationary channel at the back of the frame, said trunnion bearings being mounted to rotate around their vertical axes, rollers extending between the channels at the front and back of said frame and supported by the trunnion bearings therein, said rollers being parallel to each other and placed diagonal to said frame, means for fastening said sliding channel in its stationary channel in a plurality of positions to vary the angular relation between said rollers and the frame.

In testimony whereof I affix my signature in presence of two witnesses.

FREDERICK B. SPRASS.
